UNITED STATES PATENT OFFICE.

WALTER C. WRIGHT, OF ATLANTA, GEORGIA, ASSIGNOR TO THE LAMSON COMPANY, OF BOSTON, MASSACHUSETTS, A CORPORATION OF NEW JERSEY.

STORE-SERVICE APPARATUS AND THE LIKE.

1,142,474.

Specification of Letters Patent.

Patented June 8, 1915.

Application filed January 26, 1914. Serial No. 814,264.

To all whom it may concern:

Be it known that I, WALTER C. WRIGHT, a citizen of the United States, residing at Atlanta, in the county of Fulton and State 5 of Georgia, have invented certain new and useful Improvements in Store-Service Apparatus and the like, of which the following is a specification.

This invention relates to conveying apparatus and more particularly to what is known in the store service art as cash lift apparatus. It will be understood of course that the term cash lift is in no wise intended to restrict the apparatus to the handling of 15 cash, since merchandise, papers, etc., may be conveyed and delivered thereby with facility; and further while the preferred construction is in the nature of a lift, certain features of my invention, hereinafter referred to, are broadly applicable to store service and like apparatus generally.

One of the objects of my invention is to provide a novel means for effecting the movement of a carriage along a determined 25 path to a certain point and then to automatically unload said carriage.

A further object has been to so arrange carrier conveying means as to permit of the despatch of a loaded carrier from a station 30 at one level to a second station at a preferably, although not necessarily, higher or lower level and to there positively eject or thrust said carrier from the conveying means.

These and other objects of my invention will be hereinafter referred to and the novel combinations of means and elements whereby said objects may be attained will be more especially set forth in the claims appended 40 hereto.

In the drawing which forms a part hereof and in which like reference characters designate like parts throughout the respective views, I have exemplified a preferred construction and application of my invention; but as I am aware of various changes and modifications herein which may be made without departing from the spirit of my invention, I desire to be limited only by the 45 scope of said claims broadly considered in the light of my disclosure.

Referring to said drawing: Figure 1 is a front elevation of a cash lift apparatus. Fig. 2 is a side elevation of said apparatus; 50 and Fig. 3 is a perspective detail view of

the cash purse or carrier carriage elsewhere shown at the bottom of Figs. 1 and 2.

The apparatus given by way of exemplification comprises a track or guide-way, preferably of taut wires 1, which are connected 60 at their upper ends to a suitable bracket 2, which may be fastened to the ceiling of, for example, a balcony of a department store. The cashier's desk 3 may be located upon this balcony, while in the present case the 65 clerk's station or desk 4 is at a lower level and preferably directly beneath; and a suitable aperture is provided through the floor of the balcony through which the track-way extends.

The wires 1 are fastened at their lower extremities to a U-shaped rod or bracket 5 by means of tension adjusting bolts 6. Upon said wires is preferably, although obviously not necessarily, slidably mounted a carriage 75 or frame 7; the wires extending through lugs or eyes 8 upon the sides of said frame. When the carriage is in its lowermost position its lower lugs 8 are in engagement with spring buffers 9, the springs of which are 80 disposed around the lower ends of the guide wires. A plate 10 below these springs serves to space the wires properly at the bottom and at the top is a bumper plate 11 which to some measure serves a similar purpose but 85 which also acts as a stop for the carriage at the end of its upward travel. Plate 10 is supported by springs 12 which are attached to collars 13; the latter being adjustable upon the track wires and adapted to be set-screwed thereto.

The carriage is elevated or propelled by a cord 14, or some equivalent propelling means; cord 14 extending up from the frame 7, to which it is connected, around idlers and pulleys 15, 16, 17, 18 and 19; the two latter being mounted in a weighted block 20, to which is attached a cord 21. The pulleys are preferably so disposed as to multiply the movement of cord 21, so that in the present case a downward movement of the latter of, let us say, three feet, elevates the carriage twelve feet. The block 20 has sufficient weight to nearly but preferably not quite counterbalance the weight of the carriage.

Within the carriage 7 is a spring clip 22 which is adapted to receive and hold the coin purse or carrier 23. The latter in the present case is of the telescopic variety as indicated in Fig. 2, and is preferably made 110

of leather or the like. Transversely pivoted in frame 7, above the clip 22, is a kick-off device 24, mounted on a rod 25, upon which, preferably, also is disposed a spring 25' which as shown in Fig. 3, normally tends to hold the kick-off or pusher 24 in a determined position; a stop 26 limiting the clock-wise movement of the pusher.

At the upper station, in the apparatus given by way of exemplification, is a bent rod 27 which constitutes the preferred means for actuating the pusher at the upper station; the latter having a preferably weighted arm 24' adapted to engage the horizontal middle portion of rod 27 when the carriage is substantially at its uppermost position.

In front of the carriage and in position to receive the carrier or purse when the latter is dislodged therefrom is a tray or repository 28, although the desk 3 itself may constitute this repository. A similar tray 28' for the reception of carriers may be conveniently mounted upon bracket 5 or otherwise at desk 4.

The operation of the device is as follows: The loaded carrier is thrust into the spring clip or holder 22 by the operative at the lower station, who then pulls cord 21 which rapidly elevates the traveling frame or carriage until the latter is resiliently stopped by the bumper 11. The aperture through the floor of the balcony and, if desk 3 be of sufficient extent to surround said aperture, through said desk also, is made of such size as to permit the free passage of not only the carriage and carrier but also of the extended arm 24' of the carrier thrust or kick-off device. The latter device hence remains inactive until its operating arm or part engages the actuating means therefor, *i. e.* the bar 27; whereupon the kick-off is swung counter-clockwise, as viewed in Fig. 3 or clockwise as per Fig. 2, to positively eject the carrier from its frame into or upon its repository as indicated by dotted lines in Fig. 2. When the cord 21 is released the weight of the carriage returns it to the lower level. If, however, an operative at the upper station desires to despatch a carrier to the lower station, the weight 20 or cord 21 can be conveniently grasped and pulled down, whereby to re-elevate the carrier supporting frame. In such case the latter should not be raised sufficiently high to cause its kick-off mechanism to interfere with the insertion of a carrier into clip 22, and of course as soon as the cord or frame is released the frame and its carrier burden drop by gravity to the lower station. Here the carrier may be removed by hand or if the force of impact of the frame against the buffer be considerable, as when there is provided sufficient excess of weight of the carriage over its counter-weight 20 and the

carriage is allowed to fall relatively free for at least the last portion of its downward travel, the weighted arm 24' will possess sufficient momentum to kick or push the carrier from its clip into the receptacle 28'; whereupon the spring 25' will return the kicker to its normal position. Separate trays 29 for the storage of empty carriers may also be provided to prevent loaded carriers being overlooked by becoming mixed with empty carriers at a given station.

It will thus be seen that I have provided means for automatically unloading a coin receptacle or other carrier or article from a supporting frame or carriage at determined points in the line of travel of said carriage; that at one station such means are actuated positively while at another station the momentum of a moving part is utilized for unloading purposes; and that, if desired, the unloading means may be, in effect, common to both of said stations and may furthermore be carried by the carriage or traveler itself.

By the term "traveler" as used in the claims I contemplate any device adapted to travel along an extended way, such as is commonly provided in conveying apparatus, which may be properly so called; said device further to be adapted for the conveyance of articles such as are conveyed by store service and like elevating or conveying apparatus.

Having thus described my invention what I claim is:

1. Conveying apparatus comprising a way, two stations along said way, a traveler to move guidedly along said way, said traveler having provisions for supporting an article to be conveyed from one to the other of said stations, means to propel said traveler, and pivoted means to automatically kick said article out of said traveler at either of said stations, according to which it is traveling toward.

2. Conveying apparatus comprising a way, two stations along said way, a traveler to move guidedly along said way, said traveler having provisions for supporting an article to be conveyed from the first to the second of said stations, means to propel said traveler, and kicking means, a portion of which is mounted for movement at an angle to the line of travel of said traveler at said second station, for automatically abruptly tossing said article out and clear of said traveler at said second station.

3. Conveying apparatus comprising a way, two stations along said way, a traveler to move guidedly along said way, said traveler having provisions for supporting an article to be conveyed from the first to the second of said stations, means to propel said traveler, and kicking means for forcibly sliding said article out of said traveler side.

wise with respect to the direction of said way and abruptly casting said article clear of said traveler, at said second station.

4. Store service apparatus comprising a way, a traveler to travel thereon, said traveler having resilient means to retain an article in position thereon, means to propel said traveler along said way, and means to automatically eject said article from said resilient means when said traveler reaches a determined point in its travel along said way.

5. Store service apparatus comprising a way, a traveler to travel thereon, said traveler having resilient means to retain an article in position thereon, means to propel said traveler along said way, and means to automatically eject said article from said resilient means when said traveler reaches a determined point in its travel along said way, said ejecting means including a kick-off device and substantially stationary means at said determined point for actuating said device.

6. Conveying apparatus comprising a way, a traveler to travel either way thereon, said traveler adapted to retain an article in position therein, means to propel said traveler along said way, and means to automatically unload said traveler at one of two determined points in said way according to the direction of its travel along said way, said unloading means including an operating part disposed substantially at one of said points and adapted for engagement with a part carried by said traveler to unload the latter at said last mentioned point, said unloading means also having provisions for unloading said traveler at the other of said points by the momentum of a part thereof resulting from the movement of the traveler.

7. Conveying apparatus comprising a way, a traveler adapted to support an article and to travel in either direction along said way, means to propel said traveler along said way, and a pivotally mounted part having a weighted portion to unload said traveler by the action of the momentum

of said weighted portion resulting from a movement of said traveler, said weighted portion being adapted by its said momentum to rotate the pivotally mounted part about its pivotal axis.

8. Conveying apparatus comprising a way, a traveler adapted to support an article and to travel in either direction along said way, means to propel said traveler along said way, an ejecting part to unload said traveler laterally with respect to said way, by the action of momentum resulting from a movement of said traveler, and a weight to actuate said part by said momentum.

9. Conveying apparatus comprising a way, a traveler adapted to support an article and to travel in either direction along said way, means to propel said traveler along said way, an ejecting part to unload said traveler by the action of momentum resulting from a movement of said traveler in one of said directions, a weight to actuate said part by said momentum, and separate means to co-act with said part to unload said traveler when the latter is traveling in the opposite direction.

10. Cash lift apparatus comprising a vertical way, a light carriage to travel up and down on said way, said carriage adapted to carry an article to be conveyed, manually operated means to hoist said carriage, bumpers for said carriage at each end of its path of travel, and means to automatically unload said carriage at the respective ends of its said path.

11. Conveying apparatus comprising a way, a traveler to travel thereon and adapted to carry an article to be conveyed, means to propel said traveler along said way, and momentum actuated means to unload said article from said traveler laterally with respect to its path of travel.

In testimony whereof I have affixed my signature, in the presence of two witnesses.

WALTER C. WRIGHT.
